[57] **CLAIM**

The ornamental design for an input/output module for programmable controller, substantially as shown.

DESCRIPTION

FIG. 1 is a perspective view of an input/output module for programmable controller embodying our design;

FIG. 2 is a front elevational view thereof;

FIG. 3 is a top plan view thereof;

FIG. 4 is a bottom plan view thereof;

FIG. 5 is a rear elevational view thereof;

FIG. 6 is a side elevational view taken from the right side of FIG. 2; and

FIG. 7 is a side elevational view thereof taken from the left side of FIG. 2.
